UNITED STATES PATENT OFFICE.

RUBEN C. M. HASTINGS, OF COLUMBUS, OHIO, ASSIGNOR TO THE INTERNATIONAL TELEPHONE COMPANY, OF COLUMBUS, OHIO, A CORPORATION OF OHIO.

AUTOMATIC SELECTIVE TELEPHONE SYSTEM.

1,334,452.

Specification of Letters Patent. Patented Mar. 23, 1920.

Application filed March 10, 1915, Serial No. 13,392. Renewed April 23, 1919. Serial No. 292,236.

To all whom it may concern:

Be it known that I, RUBEN C. M. HASTINGS, a citizen of the United States, residing at Columbus, in the county of Franklin and State of Ohio, have invented certain new and useful Improvements in Automatic Selective Telephone Systems, of which the following is a specification, reference being had therein to the accompanying drawing.

10 The present invention relates to improvements in automatic selective telephone systems, and more particularly to systems employing party line circuits, one object of the present invention being the provision of a 15 selective system of telephony, in which peculiar mechanisms are disposed in all of the substation instruments and form a portion of each instrument thereof and control the shunting of the talking circuit whereby such 20 instrument may be shunted from the main line, and also whereby the instrument desired may be selected and signaled through the call-up alarm, regardless of the position of the receiver in such called instrument, 25 there being provided automatic shunting, selecting and signaling means or mechanisms to control the various elements employed, the operation of which is entirely under the supervision and control of the operator at 30 the exchange station through a selecting or master key and as set forth in the system disclosed in my reissued U. S. Patent No. 13,989, dated Sept. 28, 1915, the selecting or master key in present instance being somewhat 35 similar to the key set forth in my former U. S. Patent No. 1,061,286, dated May 13, 1913, and also containing some of the features of my former U. S. Patent No. 1,061,287 dated May 13, 1913.

40 A further object of the present invention, is the provision of a selecting disk or controller embodying somewhat similar features to that shown in my former U. S. Patent No. 1,062,004, dated May 20, 1913, the 45 present disk or controller, however, being constructed and arranged to control the shunting switch and other switches that are controlled by such shunting switch to permit of the selecting and signaling of the 50 called substation whether its receiver is upon or off the hook, and to also control such instrument regardless of the position of the receiver hook. Means is provided whereby when a person at a substation has attempted

to steal a conversation he is debarred from 55 calling any substation except the exchange station, but can be called by the exchange station, thus making it possible, though such debarred subscriber is so affected, that a calling subscriber who desires to converse with 60 the penalized subscriber may be connected for conversation with the penalized substation. It will also be further noted that although a person has left the receiver off of the hook and afterward decides to raise and 65 lower the hook, the person having use of the circuit will not be disturbed by the clicking noise occasioned in practical use at the present time.

A still further object of the present invention is the provision of a novel form of automatic shunting or lock-out device, in which the control of the various switches or contacts is placed directly under the influence of a spring and electromagnetically actuated 75 mechanism, which in turn is synchronously operated through the selecting key at the exchange station.

A still further object of the invention is the provision of a visual non-audible busy 80 signal adapted to be displayed at the substation instruments to notify at a glance whether or not the line is in condition to signal the exchange station, the same being preferably a low voltage lamp circuit having a switch controlled by the substation instrument.

A still further object of this invention is the provision of an automatically actuated synchronizer at each substation instrument, 90 whereby the controller is assured a zero or initial position should any instrument get out of step, and whereby the exchange operator may bring such instrument into synchronism by the manipulation of the selecting key.

A still further and important object of this system is the provision of a speech recording apparatus, by means of which in the event of a subscriber being absent, the 100 receiver may be left from the hook, or other means may be provided so that the exchange operator in connecting the instrument of the absent subscriber with a calling substation will connect the speech recording 105 apparatus so that the calling subscriber may record his message at the called substation, so that such message may be reproduced.

upon the return of the absent subscriber, and also whereby a speech recording and reproducing apparatus may be connected at the exchange station to receive messages of any character from the various substations.

In the present instrument there is also embodied with slight modifications the call-up alarm mechanism as set forth in my co-pending application filed August 20, 1913, Serial No. 785,818, while some of the present mechanism as relates to the controller has also been disclosed in my co-pending application filed November 28th, 1913, Serial No. 803,596.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings:—

Figure 1 is a diagrammatic view showing the circuits involved in signaling the exchange station by a substation and including the synchronizer.

Fig. 2 is a similar view showing the circuits involved in the talking operation.

Fig. 3 is a similar view of the circuits involved in selecting and calling a substation.

Fig. 4 is a similar view showing the circuits involved in the general call and busy signal.

Fig. 5 is a complete diagrammatic view of the present system equipped with local battery and exchange station energized signaling mechanism.

Fig. 6 is a similar view to Fig. 5 showing the system operated from a common battery at the exchange station.

Fig. 7 is a view in elevation of the lock-out mechanism carried at the substation.

Fig. 8 is a top plan view thereof.

Fig. 9 is a detail view on an enlarged scale of the receiver hook and the switches adjacent thereto.

Fig. 10 is a horizontal section above the disk 36, showing the means for insuring the normal position thereof.

Figs. 11 through 17 inclusive are diagrams of the periphery of the controller or disk and the relation of the paths of the operating pin of the shunt switch under various conditions.

Figs. 18 through 21 inclusive are detail views of the various positions of the disk and switches.

Figs. 22 and 23 are detail views of the selecting key and the switches controlled thereby.

In order to more fully understand the present invention, the detailed description of the controlling disks 36 and 37 and their operation, and the shunt switches or contacts 38 and 39 will be set forth. The disk 70 36, which is the main disk for controlling the shunt switch and the other switches therefrom, is provided with three ridges *a*, *b*, and *c*, and two grooves 54 and 58; this disk and the switch 38-39 constitutes the 75 shunting means to shunt the substation *S* from the line *L-L'* when necessary, being operated from the exchange through the instrumentality of the selecting key *K* at the exchange station *E* and providing a means 80 for automatically shunting from the line, the uncalled substations and connecting for communication the called substation with the calling substation for a private or non-interfering conversation, the operation of 85 the disk 36, as will presently appear, being completely and solely under the control of the selecting key from the exchange station.

For the sake of clearness, the description will follow the operation in starting with 90 the asking by a calling substation of the exchange station, and the connection by the exchange of a called substation. To therefore clearly describe the operation, we will pre-suppose that the subscriber at substation No. 1 is calling for subscriber at 95 substation No. 5 on the same party line, all of the disks 36 at this time being at what is termed zero position, (Figs. 11 through 19), with all the pins 38' carried by the 100 shunt contacts 38-39 disposed at position *a'* and as clearly illustrated in Fig. 11, of the diagrams of the peripheries of the disk 36.

Thus the ridges *b* at such point will engage the pin 38' and hold the shunt contacts downwardly against the tension of the spring 41', the detailed construction and arrangement of which will presently appear. The shunt contacts 38-39 at this position *a'* in all substations are separated and open and 110 therefore all substations are connected to the line for communication with the exchange station *E*.

In the diagram as shown in Figs. 1, 5 and 6, the receiver *R*, is removed from the hook 115 25', to permit the hook to rise and engage the contact 61, so that the signal 9 at the exchange station is energized and the exchange operator is notified that a substation is calling. As the answering and calling plugs 120 1-2, are not in place, and though the contact of the socket therewith is not made at this time, there is no danger of the electromagnet 29 being short circuited. This is effected through the following circuit, to wit:—the battery *B*, the conductor 10', the contact 209, the contact 210, the conductor 10, the signal 9, the conductor 8, the contact finger 152 of the socket *J* to the anvil 153, the conductor 105, the contacts 11 and 12, 130

the conductor 24, the line L, the line L', the conductor 7, the electromagnet 29, the conductors 5 and 6, the receiver hook 25', the contact 61, the conductors 46 and 46', the choke or impedance coil a^2 , the grounds g' and g , the conductor 10'', the contacts 212 and 213, and the conductor 10''.

The exchange operator then inserts the plug 1 in the socket J, and thus the exchange station is connected to the line for responding to the calling substation, who asks to be connected to a certain substation.

The selecting key, as described in my U. S. Patent No. 1,061,286, above referred to, is manipulated as therein set forth to select the instrument No. 5 and thus automatically, this action as will presently appear, causes the closure of a circuit to the call-up alarm 81 in substation No. 5 and consequently the signaling of such substation, all disks 36 in the various substations being actuated by the step-by-step motion imparted to the shaft 35 of the disks 36 and 37 through the instrumentality of the electro-magnet 29 which is connected at all times in circuit with the line L—L', the circuit of which will be described in full later on. Thus all of the disks 36 in every substation are caused to automatically be moved five positions, all 30 of the pins 38', except the one calling, substation No. 1, are caused to pass through the respective spaces 55' and consequently enter the respective groove 58, this being due to the fact that the receivers were upon the 35 hooks and the springs 41' were permitted to elevate the shunt contacts 38—39, unhindered from the electrical attraction of the magnet 47 upon the armature 41, which is connected to and forms a part of the swingingly mounted contacts 38—39. At this 40 time, except at substation No. 1, the circuit to the magnet 47 was opened at contact 61, and thus as before described, spring 41' was permitted to cause the pin 38' to pass 45 through the slot 55' above referred to.

In order to prevent the calling substation No. 1 from being shunted by the action of the disk 36, in such substation when the disk 36 was rotated, simultaneously with the 50 selection of substation No. 5, the pin 38' is held from entering the slot 55' (Fig. 16). It will be observed that the receiver being off the hook in substation No. 1 causes the closure of circuit at receiver hook 25' and 55 contact 61, and that such circuit, to be presently set forth, causes the energization of the electromagnet 47. This attracts the armature 41 and moves the contacts 38—39 against the action of the spring 41', to cause 60 the pin 38' to be prevented from entering the slot 55', (Fig. 6), thus causing the same to be held below the ridge b as long as properly operated. Thus it will be seen that the calling substation can be placed in communication with any of the substations con-

trolled from the exchange station, and that the shunt contacts or switch 38—39, will be opened at the calling substation No. 1 because the pin 38' is traveling through the slot 54, which is higher than the slot 58, and thus opens the contacts 38—39 and the conductors 42 and 43 connected across the receiver R, as illustrated in dash line, Fig. 2, and also producing the same result as in my former system reissued Letters Patent No. 13,989. Thus the calling substation will have its disk 36 in such position that the release of the selecting key K will permit of the return of the disk 36 to normal or zero position, or as shown in Fig. 11.

The zero or normal position is the position below the projection a' , that is one step in advance of the substation No. 1 and five steps in advance of the substation No. 5, and so on as shown in Fig. 11. It will therefore be noted that the wedge-shaped projection 38^a, which is placed upon and carried by the disk 36, (which in the present instance is the called substation No. 5), is to open the shunt switch 38—39 by the pin 38', and thus permit of the proper connection and signaling of the substation No. 5 for connection with the substation No. 1.

Under normal conditions, when the conversation between substations Nos. 1 and 5, is at an end, the receivers in both will be placed upon the hook and exchange operator will then remove the plug 1 from the socket J, and thus as set forth in my Patent No. 1,061,286 permit the automatic return of the carriage of the selecting key, and the operation and returning of all of the disks 36 to the position as shown in Fig. 11, with all parties in normal or zero position and in condition whereby any one of the substations may signal the exchange station.

Let us assume that the party at substation No. 5 after the completion of the conversation left the receiver off of the hook 25', but that the party at substation No. 1 returned the receiver to the hook, the actuation of the disk 36 due to the automatic return of the selecting key to zero position would cause the pin 38' to move under the ridge b at the slot 60, due to the fact that when the receiver was placed upon the hook, the contact 77 was closed by receiver hook 25' and consequently the circuit to the electromagnet 47 was closed when the pin 37' passed the contact 74 at the position No. 11, assuming there to be 12 positions of the key, upon the calling substation, or adjacent the slot 60, and thus the electromagnet 47 was energized and the armature 41 attracted to cause the shunt switch 38—39 to follow the dotted position, Fig. 15, so that the shunt switch was permitted to remain open and thus allow the communicating substations to remain connected to the line for again signaling the exchange station.

The pin 38' at the substation No. 5 due to the fact that the receiver was left off of the hook, was caused to pass below the ridge *b*, through the slot 60, as the circuit to electromagnet 47 in the substation No. 5 was not closed at the contact 77 and therefore the shunt switch 38-39 was moved by the spring 41' to assume the position as shown in dotted lines in Fig. 13.

10 Should the substation No. 5 with the parts in the position here described, be selected or called by the exchange station, the receiver being off of the hook, and the shunt switch 38-39 open, the disk 36 would revolve and 15 when the pin 38' has reached the tooth 38^a of the disk the switch would be permitted to open, due to the sliding of the contacts upon the tooth 38^a, at which time, the call-up alarm contacts 85 and 86, would be closed 20 and thus ring the alarm in the called substation No. 5, even though the receiver is not upon the hook and the hook is elevated (Figs. 11 and 20). This action will also cause the closing of the local talking circuit 25 at contacts 70-71, the circuit for which will be set forth later on. The subscriber at substation No. 5 observing the receiver off the hook, will vibrate the hook (Figs. 3 and 9) which action as will presently appear 30 strikes the sliding contact 151 and causes the operation of the electromagnet 47 and consequently the armature 41. Thus the switch 38-39 is moved from the groove 58 below the ridge *b* (dash lines Fig. 13) and the contacts 85-86 are opened in the call-up alarm circuit and the alarm 81 ceases ringing. The pin 38' is thus held to maintain the switch 38-39 open in substation No. 5 and the contacts 70-71 are held closed. It will thus 35 be evident that with the pin 38' traveling in the groove 58 and engaging the tooth 38^a at the substation called, (Fig. 11) that the switch 85-86 will be closed and the call-up alarm will be energized to indicate to the 40 called substation that the calling substation is desired to be placed in communication therewith. It will also be seen that provision is made for operating the call-up alarm switch 85-86 regardless of the position of 45 the receiver in the called substation, so that such substation may be properly connected and communicated with when desired.

Should the party at substation No. 5 at any time place the receiver upon the hook, 50 the next time that the exchange operator actuates the disk 36, so as to place the same at zero position, the contact 77 in substation No. 5 being closed by the hook 25', the electromagnet 47 will be energized, due to the 55 closure of the contacts 74 at the time that pin 37' on disk 36 passed the same, and as such action moved the contacts or switch 38-39 in the substation No. 5 against the action of the spring 41', the adjustment of the block 60 40 by the armature 41 will cause the pin 38'

to pass through the opening or slot 60 to assume the position below the ridge *a'* at zero or normal position, as shown in Fig. 17.

By referring particularly to Figs. 11 through 17, the various conditions arising, due to the position of the receiver upon the hook, as regards the shunt switch 38-39 are clearly illustrated, the position of the pin 38' in the various substations being as follows:

In Fig. 11, the disk 36 and pin 38' are in normal shunt open position, and the same applies when a substation is calling the exchange station.

In Fig. 12, the called substation has been selected while in Fig. 13, the pin 38' is in the position it assumes should the subscriber fail to place the receiver upon the hook at the end of the conversation and the exchange operator has released the selecting key to return the disk 36 to normal or zero position. The pin 38' in Fig. 13 is likewise in a position when calling a substation under the same conditions.

In Fig. 14, the pin 38' is shown as traveling below the ridge *a*, and the receiver is left off the hook.

In Fig. 15, the pin 38' is in the position it would assume had the receiver been properly placed on the hook after the conversation is completed and the disk 36 has been returned to normal position, while in Fig. 16 the path of the pin 38' is shown as when the subscriber is calling and up to the point of selection of the party called.

In Fig. 17 is illustrated the path of the pin 38' when a subscriber at substation had placed the receiver on the hook after improperly leaving the same off, and likewise the path of all uncalled substations, in which the receivers were properly positioned upon the looks.

In Fig. 18, the switch 38-39 is in normal or shunt open position with the pin 38' in the slot 54. It will be understood that the slot 54 is cut to a lesser depth than the slot 58, and for this reason will cause the pin 38' to open the switch 38-39 (Figs. 18 and 19).

In Fig. 19, the switch 38-39 is closed in the uncalled substation; in Fig. 20 the switch 38-39 is open and in selected or called position and the call-up circuit switch 85-86 closed; while in Fig. 21 the contacts 38-39 are open and in the position they assume at the slot 60, just previous to the returning to zero or normal position at any substation not calling.

By the elevation of the receiver hook 25', the exchange operator is notified that a substation is calling, and the plug 1 is inserted in the socket *J* so that the exchange station is connected for speech. The calling substation in the meantime having removed the receiver from the hook, has its transmitter properly connected in the usual manner,

so that the subscriber may ask for a called substation. The socket J, as illustrated in diagram in Figs. 1 through 6, is connected to the line through the conductor 15 to line L' and through conductor 105, and the normally closed contacts 11-12, and the conductor 24 to the line L.

At this time, the exchange operator inserts the other jack plug 2, in the socket J of the proper line, the called party being on another line, (but should the party be on the same line the second plug is unnecessary), and contacts 104, 152 and 153' are separated from the anvil 153 at the socket 15 J, and thus all of the circuits to be controlled are made ready for the manipulation of the selecting key. The operation of the selecting key throws impulses upon the line from the battery 23 to energize all of the electromagnets 29 in every substation, thus imparting a step-by-step movement to the shaft 35 and the disks 36 and 37. This action will cause the proper manipulation of the shunt switches 38-39, and the other contacts 44, 45, 74, 70-71, and 85-86, so that the called substation will be connected to the line with the switch 38-39 open, while the uncalled substations will have the shunt switch 38-39 held closed, and thus have their receivers shunted from the line, and there held until the selecting key K at the exchange station has been released, due to the removal of the plug from the socket, and the return of the selecting key to zero or normal position. During the return of the selecting key, the shafts in all of the substations have a step-by-step movement imparted to them as when the key was moved to selecting position, and all switches 38-39 are simultaneously placed in shunt open position, with all of them connected to the line.

The manipulation of the selecting key after the calling plug 2 is inserted in the socket J will cause the throwing of successive impulses upon the line from the battery 23 and consequently affect the electromagnets 29, as each one of the electromagnets is connected to the line and in series through the conductors 5 and 7. At the selecting key, in conjunction with the contacts 11-12, are the contacts 20-21, which are operated by the selecting key as before stated, the automatic opening and closing 55 of the same connecting and disconnecting the battery 23 to the line L-L' and thus energizing all of the electromagnets 29 through the following circuit, to-wit:-

The contacts 20-21, (see heavy lines Fig. 60 3), the conductor 22, the battery 23, the choke or impedance coil c², the conductors 24', 24 and L to the other side of the line L', the conductor 7, the electromagnet 29, of all substations, the conductor 5, the conductor 15, the contact 14 of the jack J, tip of

the plug 1, the conductor 3, the choke coil c², the conductor 4', the ringing and answering key K, the conductor 105, and contact 20.

The choke coil c² is so situated as to bridge the circuit through either jack plug, acting 70 as a short circuit to each plug toward the direct current from the battery 23, but impervious to the high frequency impulses of the secondary talking current, and also allowing it an unimpeded path from the 75 plug 1 to the plug 2, or to the listening key K'. The electromagnet 29 is a lifting electromagnet constructed with an iron shield so as to be impervious to a secondary talking current of high frequency impulses, but to 80 be pervious to the direct current from the battery 23.

Whether the receiver hook 25' is in its lowermost position, with the receiver R thereupon, or not, the circuit with the line 85 L' is complete through the conductor 5, the electromagnet 29 and the conductor 7.

When the various electromagnets 29 in all of the substations are simultaneously energized, the armatures 30 are attracted 90 against the action of their respective springs 30', and operates the respective operating and arresting pawls 31-32, which in turn actuates the respective operating and arresting ratchets 33 and 34, keyed upon the 95 rotatable shaft 35. This shaft in the present instance is carried by the base B' (Figs. 7 and 8), which carries the majority of the substation selecting and lock-out mechanism and is adapted to be placed in any standard 100 telephone desk set or wall set. Thus the present device is readily installed and positioned in place, and due to the spring 41', and the electromagnet 47, the present mechanism may be operated regardless of the 105 position in the instrument or set, this peculiar arrangement permitting the same to be placed at any angle and be carried bodily on the door of a box set.

When the shaft 35 has the step-by-step action imparted thereto, the disks 36 and 37 are operated, and the various or desired operations controlled by said disks are carried out.

As before described, the shunt controlling 115 contacts 38 and 39 are operated by the peripheral portion of the disk 36, the pin 38' thereof being adapted to follow the dotted positions, as illustrated in Figs. 11 through 17, and thus consequently control the shunt 120 contacts 38 and 39 according to the position of the receiver hook 25' in the substations.

Disposed in the path to be engaged by the pin 37' of the disk 37, are two contacts 44 and 74 (Fig. 3), the contact 44 having 125 led therefrom, a conductor 46 connected to the contact 61, (the receiver hook being disposed to make the contact when elevated), and thus complete the circuit through the conductors 80 and 66, the battery 65, the 130

conductors 51 and 51', the electromagnet 47, the conductor 53, and the contact 45 which rides on the disk 37, and the pin 37'. Disposed to actuate the block 40, which is shifted so as to permit of the swinging of the contacts 38 and 39 and also the contacts 70 and 71, and 85, transversely of the peripheral edge of the disk 36, is the magnet 47 and its armature 41, and by this construction and arrangement the contacts 38 and 39 are separated or permitted to engage, according to the desired condition, the circuit and the electromagnet 47 being provided to move the contacts in one direction while the spring 41' moves them in the opposite direction.

The contact 61 is disposed to be engaged by the receiver hook 25' upon the elevation of the hook, while the contact 77 is similarly controlled, the closure at the contact 61 causing the energization of the electromagnet 47 at the time the pin 37' is passing the contact 41, as will presently appear, the same as before stated occurring when the receiver R is off the hook 25' and the hook is elevated. The energization of the electromagnet 47 attracts the armature 41 and causes the movement of the contacts 38-39 in a direction opposed to the spring 41', and the said contacts 38-39 will be held in this position by the pin 38' and the ridge b, as the pin 38' is at that time below the said ridge. This action permits the pin 38' to separate and hold open the shunt contacts 38-39, and the particular substation is connected to the line.

As before stated, the periphery of the disk 36 is so mutilated or constructed as to provide the three circumferential ridges a, b and c, which define the two grooves 54 and 58, the disk 36 also carrying the tooth 38a, which is placed at a position corresponding to the step or position necessary to signal the substation, this position differing for each substation on the line. The ridge b which is the center ridge of the disk is provided with the shallow slot 55' to form a connection or means of communication with the recess or groove 54 and thus permit the pin 38' to move only from the groove 54 to the groove 58, as the groove 58 is the deeper groove of the two grooves 54 and 58. The ridge b is also provided with a slot 60, which permits the pin 38' to move into the groove 58, all of which actions are due to the spring 41' and the rotation of the disk 36 with the electromagnet 47 deenergized. When the pin 38' is upon the tooth 38a, the contacts 85-86 of the call-up alarm circuit to the alarm 81, as well as the contacts 70-71, are closed, thus energizing the call-up alarm 81 at the selected substation. The pin 38' when passing through the groove or slot 55', causes the contacts 38-39 to be moved transversely

of the periphery of the disk 36, and the pin 38' is permitted to enter the groove 58 adjacent the ridge a, and thus closes the contacts 38-39 and opens the contacts 70-71 and 85-86. (Figs. 18 and 19.)

70

As may be found necessary and expedient, the disk 36 may be provided with any number of teeth 38a, this being regulated according to the number of substations employed, and each of said teeth, as before described, provides means for the control of the contacts 38-39, 70-71 and 85-86, so that the same may be properly opened and closed for connecting a called substation to a calling substation, or for shunting all except the calling and called substations from the line, the groove 54 in all of the substations being so designed as to prevent the closure of the contacts 38-39 of the calling and called substations.

85

To allow the passage of the pin 38' from the groove 58 to the shallower groove 54 (Fig. 21), the pin is raised by passing the projection in the slot 60, which is on a level with the bottom of the groove 54. Thus at the slot 60, the pin 38' may move transversely of the disk 36 in either direction between the grooves 54 and 58, but at slot 55' it may only move from the groove 54 to the groove 58, due to the greater depth of the groove 58, and a shoulder formed thereby.

90

In order to provide a means for properly connecting the transmitter T to the battery, the contact 61 is disposed in the path to make contact with the receiver hook 25' (Fig. 2), 100 when the hook is elevated the circuit thus formed comprising the conductors 46 and 67, the transmitter T, the conductor 67, the primary of the induction coil 68, the conductor 69, the closed contacts 70-71, the conductors 51' and 51, the battery 65, the conductors 66 and 80, and the receiver hook 25'.

105

The contacts 70-71 are so disposed with relation to the shunt contacts 38-39, that the same will open when the contacts 38-39 are closed, thus permitting the opening of the local battery circuit, so that the manipulation of the hook 25' to elevated position will not cause the closure of the local battery circuit; it being necessary that the contacts 38-39 be opened to permit the closure of the contacts 70-71, and thus properly connect the local battery circuit so that when the receiver hook 25' in the called or selected substation is elevated, the local battery circuit will be closed and connected to the transmitter.

110

The spring contact 74, which is controlled by the pin 37' (Fig. 3) and is connected by means of the contact 77 to the receiver hook 25', at the time when the receiver hook is depressed and the receiver is thereupon, will close the circuit to the electromagnet 47, through the conductor 75, the contact 74, the pin 37', the disk 37, the brush 45, the con-

115

125

130

ductor 53, the electromagnet 47, the conductors 51' and 51, the battery 65, the conductors 66 and 80, and the receiver hook 25'. This circuit provides a means to return the 5 pin 38' to the proper groove of the disk 36. When such calling substation has completed the conversation with the called substation and the receiver has been placed upon the hook and the selecting key K at the exchange 10 station has been released by the removal of the plug from the jack, as before described, the disks 36 and 37 will be returned to initial or zero position by the rotation of the shafts 35 in all of the substations. This 15 same condition is employed to move the pin 38' into the groove 58, through the slot 60, when a party using the instrument has neglected to place the receiver upon the hook at the completion of the conversation, the 20 spring 41' at this time pushing the pin 38' from the groove 54 to the groove 58, after the exchange operator has disconnected the calling substation by the return of the carriage of the selecting key to normal or zero 25 position.

The contacts 85 and 86 are provided as a means for connecting the call-up alarm 81 at the substation, so that when the disk 36 is operated and causes the closure of the contacts 85-86, the call alarm 81 will be energized through the following circuit, to-wit:—the contacts 85-86, the conductor 82, the call-up alarm 81, the conductor 66, the battery 65, and the conductors 51 and 51'. Thus the call-up alarm will be energized and will remain energized until the receiver is removed from the hook, or the hook is vibrated, to open the call-up alarm circuit at contacts 85-86 by the removal of the pin 38' from the tooth or depression 38^a and into the groove 54. The call-up alarm in this instance, as herein noted, is controlled by the local battery, or a battery at the substation and is so constructed as to prevent 40 the operation thereof caused by the engagement of the tooth or depression 38^a in the uncalled substations when the pin 38' is adjacent such point.

Should the subscriber at the called substation for any reason have left the receiver R off of the hook, the call-alarm will be operated regardless of the position of the hook. When the disk 36 is being rotated by the manipulation of the selecting key, and 50 just as the pin 38' reaches a position approximately a zero position, the spring 41', not being opposed by the electromagnet 47, will cause the pin 38' to pass through the slot 60, or as clearly illustrated in Fig. 13, so that 55 the next time the substation is called by the exchange station, the pin 38' owing to the party not placing the receiver upon the hook, will be caused to travel in the groove 58, thereby placing it in a position to be engaged 60 by the tooth or depression 38^a. Thus it will

be evident that the alarm 81 will continue to ring similarly to the before mentioned ringing when the receiver was upon the hook, and that means are provided to cause the operation of the call-up alarm regardless 70 of the position of the receiver hook, (Case E).

The contacts 85-86 are operated by the contact 38 of the shunt controller, so that when the shunt contacts 38-39 are closed, 75 the contacts 85-86 are open. By this arrangement the uncalled substations will be shunted from the line and will also have the circuit controlling the call-up alarm open, so that such call-up alarm circuit cannot be 80 operated until the shunt contacts 38-39 are opened.

When the receiver hook 25' is vibrated to cause the call-up alarm 81 to cease ringing, it does so by means of the energization 85 of the electromagnet 47, which attracts the armature 41 and moves the pin 38' from the tooth or depression 38^a into the groove 54. This is accomplished by means of a contact 25 carried by the receiver hook 25' 90 (Fig. 9), or the hook 25', and a contact 151, which is disposed in a mid-position to be engaged by the hook during its movement but not at either extreme position. This closure causes the energization of the electromagnet 47, which attracts its armature 41 and swings the pin 38' transversely of the disk 36 out of engagement with the depression 38^a and into the groove 54, which permits the opening of the contact 85-86 100 and the call-up alarm circuit. The depression or tooth 38^a is formed to be flush with the ridge b of the disk 36, and consequently pushes the contacts 38-39, 70-71 and 85-86 into the extreme position, as shown 105 in Fig. 20. The electromagnet 47 is operated for this function through the following circuit, to-wit:—the electromagnet 47, the conductors 51' and 51, the battery 65, the conductors 66 and 80, the receiver hook 110 25', or its contact 25, the contact 151, and the conductors 53' and 53.

When the receiver has been left from the hook, the pin 38' is pushed to the groove 58 by the spring 41', as the selecting key K 115 returns the disks 36 to zero position.

Mounted upon the disk 36 at zero position in the groove 58 is the tooth 60^a, which performs a function similar to the tooth 38^a, ringing the call-up alarm at the substation 120 whose receiver has been improperly elevated and thus permitting the pin 38' to be engaged by this pin 60^a. At the same time the drop, or signal 9 at the exchange station is energized because the withdrawal of the plug 125 from the jack has caused the closing of the drop signal circuit at the contacts 152-153. Hence the exchange operator again inserts the plug, and the substation in the above condition will have its call-up alarm ener- 130

gized and attention drawn to the fact after answering the call that the receiver was off the hook. The replacing of the receiver causes the energization of the electromagnet 17 by the contacts 151 and 25, or the hook 25', and consequently attracts the armature 41 and moves the pin 38' transversely of the disk 36 and the pin or tooth 60' and into the normal position in the groove 54.

19 Disposed in the exchange station for the actuation of the electromagnet 99 of the selecting key K. (Fig. 3), said electromagnet controlling the armature 69', as particularly set forth in my Patent No. 1,061,286, are the contacts 95 and 96, which are closed by the carriage of the selecting key K, while in operative position, such closure closing the circuit as follows, to-wit:—the contacts 95—96, the conductor 98, the electromagnet 99, the choke coil c', the conductor 100, the battery 93, the conductor 94', the choke coil c'', the conductors 94'' and the conductor 105, and thence through one of two circuits which will presently appear, to-wit:—one 25 circuit which stops the motion of the carriage 300 (Fig. 23) of the key K, after the proper number of impulses have been sent upon the line, is completed by the conductor 105', the contacts 101—102 and the conductors 103 and 94 to the contact 95. The other circuit which releases the carriage of the key at the end of the conversation, is operated by the removal of the plug from the jack socket, and permits the contacts 30 153 and 153' to close the circuit to the electromagnet 99, includes the conductor 105, the contact 153—153', conductors 103 and 94 to the contact 95. Thus the contacts 35 95 and 101—102, and also 153—153', control the energization of the electromagnet 99.

In order to provide a signaling means at each substation to indicate when the line is busy, a pair of spring contacts 157—158 are 45 disposed in the path of the pin 37', the circuit controlled thereby being as follows, to-wit:—the contacts 157—158, the conductor 159, the signal lamp 161, the conductors 162 and 51, the battery 63, the conductors 50 66 and 66'' to the contacts. Thus at any position except zero position, the switch is closed and the signal lamp energized, the passing of the pin 37' causing the opening of the switch and this action being at zero 55 position.

This signal lamp is of an exceedingly low voltage and may be disposed within the telephone box C and readily observable through the aperture formed therein, or 60 mounted at any convenient place exteriorly of the box.

In order to provide a means, whereby a conversation may be recorded, especially in the case where the called subscriber is absent, a sound recording and reproducing

machine M. (Fig. 5), either in the form of a mechanical machine such as a dictaphone or the telegraphophone may be employed, the circuit for controlling the starting and stopping of the same being actuated by the pin 70 37' of the disk 36 through the switch 163—164 and the hand operated switch 165', which is only permitted to be closed when it is desired to record a conversation. To accomplish this the subscriber notifies 75 the exchange operator, so that the exchange operator when calling the substation can notify the calling substation that the party is absent but that the recording machine can be connected to record any message and 80 then connects the calling subscriber for conversation.

The circuit for connecting the machine M, includes the battery 160, the conductor 168, the contacts 163—164, the conductor 165, the 85 switch 165', the motor 166, and the conductor 167.

When the telegraphophone is employed, the record is recorded magnetically upon a steel or magnetizable wire, or where the dictaphone is employed, the usual wax or composition cylinder may be employed, and constructed so that several in succession may be connected to record a complete message or a 90 number of messages.

Where the telegraphophone is employed, the coil for recording the message is connected directly in the talking circuit and thus is in series or multiple with the receiver and transmitter, while where the dictaphone is 95 employed the receiver may be positioned, when removed from the hook, directly in the horn thereof, the present invention residing in the fact that the control of the telegraphophone or dictaphone when the receiver is off 100 the hook is automatic and actuated by the shaft 35 which carries the disks 36 and 37.

As the exchange station at night is not called frequently as during the day time, the night bell or signal 174 is provided, and is 110 controlled by the signal or drop 9 and the contact 173 to receive its current from the battery b³ at the exchange station.

A similar arrangement in the form of a 115 buzzer 175 may be used in the daytime, where calls are infrequent and it is desirable to attract the exchange operator's attention that the drop 9 has been actuated.

To facilitate and insure the accurate operation of the disk 36 in all substations, a synchronizing device (Fig. 10) is disposed in 120 each substation, and consists of a polarized relay r', which controls an electromagnet 203 and its armature 206. This armature carries an arm 207 positioned to engage at 125 the proper point a pin or block 208 mounted on the upper surface of the disk 36, this being accomplished when the arm is swung inwardly. This arm by engaging the pin 208 forms a lock to hold the disk 36 against 130

further motion, and since the pin is so placed as to be engaged at the zero position only, all of the disks 36 will be arrested at this point, regardless of the number of impulses sent by the key K. The operation of the electromagnet 205 is controlled by the relay r^2 , as before stated, and this relay is controlled in turn by a direct current flowing between the ground and the line and reversible at the exchange station. This current is supplied by the drop controlling battery B (Figs. 1, 5 and 6,) which normally supplies its current from the line L' through the conductors 80, 66 and 225 to the relay r^2 , thence by way of the conductor 224 to the ground g' . The relay, as before stated, is polarized, and does not respond to this normally flowing current. To operate the relay therefore and consequently the electromagnet 205, this current is reversed at the exchange station by the key K, when it is released by the removal of the jack plug from its socket.

Positioned upon the frame of the key K (Figs. 22 and 23), are the contacts 209, 210, 211, 212 and 213, operated simultaneously with the contacts 101—102 by the barrel 18. It will be observed that this barrel is like that of my U. S. Patent No. 1,061,286, except for a raised portion or ridge 214, at the rear end of the barrel 18, and a greater number of notches upon the stepping portion 17. This barrel causes the contacts 210—212 to move inward or outward to engage alternately the contacts 209—211 or 211—213, thus providing a simple yet efficient current reverser or pole changer. The change in the flow of the current takes place the instant that called substitution is selected, but does not affect the relay r^2 until the current is flowing through the line by the removal of the plug from the socket at the exchange station and the consequent closing of the contacts 153—153', which also releases the key K. The key, then being released, actuates through the impulses sent out on the line of the electromagnets 29 and steps them until the respective pins 208 engage the respective arms 207, the zero position of the disks, the disks being held in such position even though the key continues to affect the sending of impulses out on the line. During this time, from the instant of the release of the key, the contacts 210—212 engage the contacts 209—211, respectively, assuming this position due to the cut-away portion 19 of the barrel 18. When the carriage has returned to normal position, however, the ridge or ring 214 lifts the contacts 210—212 from this position to the normal position in engagement with 211 and 213, respectively. Thus it is apparent that the arms 207 after having adjusted their respective disks 36 will be permitted to return to their former position, out of the path of the posts 208,

due to the deenergization of their respective electromagnets 205 non-effective to the reversed current.

The general call is operated by means of a relay r connected between the line and the ground, as shown, or bridged across the electromagnet 29. This relay is operated by the alternating current generated from the generator G at the exchange station E, that is, it is sensitive to alternating current of a low frequency and ineffective to direct current. In the diagram (Fig. 4), the generator G is connected to the line by means of the plug and socket and the operating of the ringing key K', as is usual. From the key K', the circuit may be traced through the conductor 204 to the generator G, the conductor 203, the ground g , the ground g' , the condenser d , the conductor 200, the relay r , and the conductor 5 to the line L'. The energization of this relay closes the following circuit to the call-up alarm 81, to-wit:—the contact 200', the conductors 201 and 82, the call-up alarm 81, the conductor 66, the battery 65, the conductor 202, and the armature r^3 of the relay r . Consequently all of the substations are notified simultaneously that the exchange station is calling, and the exchange operator can then give all substations the same message, which in country or outlying districts is desirable, in cases of fires, floods, general information, and weather reports.

In Fig. 6, is shown an adaptation of the present invention to a common battery system, the energy for operating the various electromagnets and relays and other parts of the instruments at the substations being the same, except that for operating the electromagnet 29, and the relay r . This main current is derived from the battery B, at the exchange station E. The insertion of the jack plug in the socket does not cut off the battery B from the line, but merely short circuits the drop signal 9. The energy is made available at the receiver hook 110, as before set forth, but in this case through the following circuit, the battery B, the conductor 10'', the contacts 209—210, the conductors 10 and 218, the contacts 219—14 of the socket J, the conductor 15, the line L', or from the conductor 15 to the conductor 230, the choke coil c^2 , the conductor 231, the conductor 105, the contacts 11—12, the conductor 24, to the line L, to the substation S, the conductor 7, the electromagnet 29, the conductors 5 and 6, and the hook 25'. Here it is made available to any of the circuits, as for example the talking circuit, to-wit:—the contact 61, the conductors 46 and 67', the transmitter T, the conductor 67, the primary of the induction coil 68, the conductor 69, the contacts 70—71, the conductors 51' and 51, the choke coil c^3 , the ground g' , the ground g at the exchange station E, the choke coil c^4 , the conductor 10', the contacts 130

212--211, and the conductor 10". Similarly 47 and 205 are energized, as is also the call-up alarm 81 and the signal lamp 161. The actuation of the substation instrument, 5 is in all respects identical to the local battery system before described in connection with Figs. 1 through 5.

What is claimed, is:—

1. In a selective system of telephony, the 10 combination with an exchange station and a plurality of substations connected electrically for the transmission of intelligence, of a call-up alarm at each substation, a selecting device at the exchange station, and two 15 mechanisms at the substation and under the influence of the selecting device at the exchange station, whereby one call-up alarm is operated or all are operated simultaneously.
2. In a selective system of telephony, the 20 combination with an exchange station and a plurality of substations connected electrically for the transmission of intelligence, said exchange station being provided with 25 a selecting device and each substation being provided with a receiver and a receiver hook, of a call-up alarm at each substation, and two mechanisms at each substation and under the influence of the selecting device at 30 the exchange whereby the call-up alarm at any one of the substations may be operated regardless of the relative positions of the receiver and receiver hook, or whereby all of the call-up alarms in all substations may 35 be operated simultaneously.
3. In a selective system of telephony, the 40 combination with an exchange station and a plurality of substations connected electrically for the transmission of intelligence, of a selecting device at the exchange station, a call-up alarm at each substation, and two 45 mechanisms under the control of the selecting device whereby all call-up alarms can be operated simultaneously, or one at a time.
4. In a selective system of telephony, the 50 combination with an exchange station and a plurality of substations connected electrically for the transmission of intelligence, of a selecting device at the exchange station, a rotary controller at each substation 55 and influenced only by the selecting device, and means for holding each controller in initial or zero position during the returning of the controllers to such position should such controller get out of synchronism.
5. In a selective system of telephony, the 60 combination with an exchange station and a plurality of substations connected electrically for the transmission of intelligence, of a selecting device at the exchange station, a receiver in each substation, a switch 65 controlled shunt connection across the receiver, a controller for the switch under the influence of the selecting device, a call-up alarm in each substation, a circuit including a source of electrical energy, the call-up alarm, and two switches, one of the switches being controlled by the controller to individually close the call-up alarm circuit, and the other switch being controlled from 70 the exchange station and simultaneously closed in all substations to energize all call-up alarms in the system simultaneously.
6. In a selective system of telephony, the 75 combination with an exchange station and a plurality of sub-stations connected electrically for the transmission of intelligence, of a selecting device at the exchange station, a receiver in each sub-station, a switch controlled shunt connection across the receiver, 80 an electrically actuated rotary controller for opening and closing the shunt switch, a call-up alarm in each sub-station, a circuit including a source of electrical energy, the call-up alarm and two switches at each substation, one of the switches being closed by its controller when the shunt switch is opened, and an electrical device in each sub-station operative simultaneously with the rotary controller whereby said electrical device and the rotary controller are operable from the exchange for actuating all of the aforementioned switches and whereby all of the call-up alarms may be energized simultaneously. 85
7. In a selective system of telephony, the 90 combination with an exchange station and a plurality of substations connected electrically for the transmission of intelligence, of a selecting device at the exchange station, 95 a receiver in each substation, a switch controlled shunt connection across the receiver, a rotary controller for the switch and under the influence of the selecting device, and a call-up alarm circuit including a source of electrical energy, a switch and an alarm at the substation, the switch thereof being controlled by the shunt switch and the controller. 100
8. In a selective system of telephony, the 105 combination with an exchange station, and a plurality of substations connected electrically for the transmission of intelligence, of a selecting device at the exchange station, a receiver, receiver hook and a shunt connection across the receiver at each substation, a controller for the shunt connection at each substation and under the influence of the selecting device, whereby the shunt connection is opened and closed entirely from the exchange station, a call-up alarm in each substation, a circuit including the call-up alarm, two parallel connected switches, and a source of electrical energy, one of said switches being controlled by the controller and closed when the shunt switch is opened, and means controlled from the exchange station for closing all of the other switches to energize all of the call-up alarms in the system simultaneously. 110
9. In a selective system of telephony, the 115 combination with an exchange station, and a plurality of substations connected electrically for the transmission of intelligence, of a selecting device at the exchange station, a receiver, receiver hook and a shunt connection across the receiver at each substation, a controller for the shunt connection at each substation and under the influence of the selecting device, whereby the shunt connection is opened and closed entirely from the exchange station, a call-up alarm in each substation, a circuit including the call-up alarm, two parallel connected switches, and a source of electrical energy, one of said switches being controlled by the controller and closed when the shunt switch is opened, and means controlled from the exchange station for closing all of the other switches to energize all of the call-up alarms in the system simultaneously. 120
10. In a selective system of telephony, the 125 combination with an exchange station, and a plurality of substations connected electrically for the transmission of intelligence, of a selecting device at the exchange station, a receiver, receiver hook and a shunt connection across the receiver at each substation, a controller for the shunt connection at each substation and under the influence of the selecting device, whereby the shunt connection is opened and closed entirely from the exchange station, a call-up alarm in each substation, a circuit including the call-up alarm, two parallel connected switches, and a source of electrical energy, one of said switches being controlled by the controller and closed when the shunt switch is opened, and means controlled from the exchange station for closing all of the other switches to energize all of the call-up alarms in the system simultaneously. 130

9. In a selective system of telephony, the combination with an exchange station and a plurality of substations connected electrically for the transmission of intelligence, of a selecting device at the exchange station, a receiver, a receiver hook and a switch controlled shunt connection across the receiver at each substation, a call-up alarm circuit including a call-up alarm, a source of electrical energy, and a switch at each substation, the latter switch being controlled by the shunt switch, and means in each substation and controlled solely by the selecting device for actuating the shunt switch.
10. In a selective system of telephony, the combination with an exchange station and a plurality of substations connected for the transmission of intelligence, of means located at the exchange station for causing intermittent impulses to flow through the line to the substations, an electromagnetically operated step-by-step device in each substation operated by such impulses, and means for insuring a synchronized position of the latter device when it reaches its initial position.
11. In a selective system of telephony, the combination with an exchange station and a plurality of substations connected electrically for the transmission of intelligence; of means located at the exchange station for causing intermittent impulses to flow through the line to the substations; an electromagnetically operated step-by-step device in each substation operated by such impulses; a call-up alarm circuit at each substation and including a source of electrical energy, a switch, and an alarm, said switch being opened and closed by the step-by-step device; and an auxiliary circuit including said alarm and a source of electrical energy at the exchange; whereby all of the call-up alarms may be energized simultaneously or separately.
12. A substation for a selective telephone system, including an electro-magnetically operated step-by-step device; a shunt switch controlled thereby; a call-up alarm circuit, having a source of electrical energy, a switch controlled by the shunt switch, and an alarm; an electrically actuated switch operative to a current of a different characteristic than the step-by-step device; and a partial circuit controlled thereby and including the alarm.
13. A lock-out and shunt cop roller for a selective telephone system, including a step-by-step actuated disk having a plurality of peripheral grooves and ridges, said grooves being in communication with each other, a swinging support disposed for reciprocation longitudinally of the disk, a spring for holding the support in one extreme position, an electric motor for moving the support in opposition to the spring, and a two membered switch carried by the support and having one of its members controlled by the grooves and ridges of the disk.
14. A lock-out and shunt controller for a selective telephone system, including a step-by-step actuated disk having a plurality of ridges providing two circumferential grooves, one of greater depth than the other, two resilient switch members, one of which is provided with a pin for disposition in one of the grooves at a time, said grooves being in communication with each other at predetermined intervals, a swinging support carrying both switch members and mounted to move the switch members longitudinally of the disk, a spring for holding the support in one direction and to hold the pin against one of the ridges of the disk at a time, and an electric motor for swinging the support in opposition to the spring.
- In testimony whereof I affix my signature in presence of two witnesses.

RUBEN C. M. HASTINGS.
